UNITED STATES PATENT OFFICE.

ISAAC MOELLER, OF NEW GLASGOW, NOVA SCOTIA, CANADA.

REVERSIBLE STRUT FOR RAILWAY BRAKE BEAMS.

Application filed July 17, 1922. Serial No. 575,740.

To all whom it may concern:

Be it known that I, ISAAC MOELLER, a subject of the King of Great Britain, residing at the city of New Glasgow, in the Province of Nova Scotia and Dominion of Canada, have invented certain new and useful Improvements in Reversible Struts for Railway Brake Beams, of which the following is a specification.

This invention relates to improvements in reversible strut for railway car brake beams, and the objects of the invention are to provide simple and effective means which will enable the strut to be adjusted so that it may be angularly disposed on either side of the brake beam to thereby enable the strut to be used with levers slanted to the right or to the left.

Further objects of the invention are to provide improvements in the manner of attachment between the strut and the brake beam. Further objects still are generally to improve and simplify the construction of the device to enable the various parts to better perform the functions required of them.

It consists essentially of the improved construction hereinafter described in detail in the accompanying specification and drawings.

In the drawings:

Figure 1 is a side elevation of an embodiment of the invention, and the brake beam to which it is attached.

Figure 2 is a sectional elevation on the line 2—2, Figure 1.

Figure 3 is a sectional elevation on the line 3—3, Figure 2.

Figure 4 is a plan of the connecting member in position on the brake beam.

Figure 5 is a plan view showing the end of the strut.

Figure 6 is an inverted plan showing the under side of the connecting member in position on the brake beam.

Figure 7 is an inverted plan showing the bottom of the strut.

Figure 8 is a sectional detail on the line 8—8, Figure 2.

Figure 9 is a sectional detail on the line 9—9, Figure 8.

Figure 10 is a sectional detail on the line 10—10, Figure 2.

Figure 11 is a sectional detail on the line 11—11, Figure 2.

Figure 12 is a perspective detail showing the head of the strut.

In the drawings, like characters of reference indicate corresponding parts in all the figures.

Referring to the drawings:

A indicates the compression member on the brake beam, of usual channel form, and B the tension rods, also of usual form and attached in the usual way to the ends of the compression member, which ends also carry the usual brake heads C. D indicates the strut in the centre, extending between the compression and tensioning members, and E the connecting member by which the head of the strut is connected to and held in position on the compression member.

The strut D may be made of malleable iron, cast steel or possibly of pressed steel or tubing. It is tubular in form having a tapered neck 10 at the upper end and a squared body portion 11 having a transverse slot 12 for the brake lever, the sides being formed with suitable perforations 13 to receive the pivot pin of the lever. The lower end of the strut D is formed with cross grooves or notches 14 and 15 set at an angle of forty degrees to each other and in which the tension rod B is designed to fit. The rod fitting in one notch of the lever is slanted to the left of centre and in the other notch when it is slanted to the right of centre.

The connecting member E extends completely around and is slidably mounted upon the compression member A. It is thus rectangular in cross section and the inner corners are preferably recessed as at 16 to obtain a perfectly clean corner on casting without the expense of machining.

The upper end of the strut D is formed with a key head 17 designed to extend through a key socket 18 in the connecting member E. As shown in Figure 6, the socket is circular in form having diametrically opposite pairs of recesses 19 designed to receive projections or tongues 20 on the end of the strut, the relative position of the tongues and recesses 19 being such that the head will be locked in the connecting member E when either of the grooves 14 or 15 is in engagement with the tension member B.

The end of the strut is further held in position by means of a projection 21 on the under side of the compression member A.

which may be formed by pressure from the opposite side, which projection is designed to fit a cored hole 22 in the end of the strut D.

5 The lower edge of the connecting member may be conveniently provided with reinforcing flanges 23 while the weight of the sides may be reduced by openings 24 formed therein.

10 The apertures 13 may be formed on the inner side with sleeves 25 designed to embrace and give support to the pivot pin of the lever.

15 In assembling the brake beam with the present invention, the connecting member E is first applied on the compression member A. The head 17 of the strut D will then be entered into the socket 18 and turned to the degree desired. The tension rod will 20 then be applied along with the usual bolts, nuts, etc., and tightened up in the usual way. The strut, having the double grooves 14 and 15 on the ends, will enable it to be placed in either right or left hand position 25 and if by chance, the beam should be made up incorrectly, the only thing that has to be done is to loosen the nuts on the end and turn to the other position. When the tension member is tightened up, the strut beam 30 will be firmly held in position not only by the connecting member, but also by the engagement between the projection 21 and the recess or opening 22.

35 As many changes could be made in the above construction and many widely different embodiments of my invention within the scope of the claims, constructed without departing from the spirit or scope thereof, it is intended that all matter contained 40 in the accompanying specification and drawings shall be interpreted as illustrative and not in a limiting sense.

45 What I claim as my invention is:

1. A reversible strut for brake beams comprising a strut having cross grooves at one end designed to fit over a tension member and a key head at the opposite end to the connecting member adapted to be slidably mounted, the compression member having a 50 socket to receive the key head and means for retaining the connecting member in longitudinal adjusted position on the compression member.

55 2. A brake beam comprising a compression member, a tension member, a strut ex-

tending centrally between the compression and tension member, the said strut having means to engage the tension member in either of two angularly adjusted positions having interlocking means at the opposite 60 end, a connecting member slidably mounted on the compression member having means to interlock with the interlocking means on the head of the said strut and means for retaining the connecting member in longitudinal adjusted position on the brake beam. 65

3. A brake beam comprising a compression member, a tension member, a strut extending centrally between the compression and tension member, the said strut having 70 means to engage the tension member in either of two angularly adjusted positions having interlocking means at the opposite end, a connecting member slidably mounted on the compression member having means to interlock with the interlocking means on the head of the said strut and means for retaining the connecting member in longitudinal adjusted position on the brake beam, the said means comprising a projection on 75 the brake beam adapted to engage a suitable recess in the end of the strut.

4. The device as claimed in claim 1 in which the connecting member is of rectangular cross section and formed with reinforcing flanges on the underside. 85

5. The device as claimed in claim 1 in which the connecting member is rectangular in form extending completely around the compression member and formed with apertures in the side designed to reduce the weight thereof. 90

6. The device as claimed in claim 2 in which the compression member is of channel form and the connecting member is 95 formed on the underside with recessed portions opposite the corners of the said channel member.

7. The device as claimed in claim 1 in which the head of the strut is formed with 100 diametrically opposite pairs of tongues designed to fit suitable recesses in the socket formed in the connecting member.

In witness whereof I have hereunto set my hand in the presence of two witnesses. 105

ISAK MOELLER.

Witnesses:

MINNIE G. ROR,
R. DOUGLAS GRAHAM.
